UNITED STATES PATENT OFFICE

FRANK E. QUEENEY, OF TEANECK, NEW JERSEY, ASSIGNOR TO INTERNATIONAL MOTOR COMPANY, OF NEW YORK, N. Y., A CORPORATION OF DELAWARE

GAS ELECTRIC DRIVE

Application filed October 11, 1926. Serial No. 140,764.

This invention relates broadly to a drive or transmission for self-propelled vehicles and more specifically to the disposition of circuits and their control in what is known in the trade as gas-electric drives for motor vehicles, rail cars and the like. In such vehicles an electric generator is driven by an internal combustion engine and current from the generator is utilized in one or more motors turning the driving wheels of the vehicle. Heretofore in gas-electric drives it has not been found possible to so associate a generator and an internal combustion engine that the speed-torque curve of the generator would follow, that is, coincide closely with the power curve of the engine, but in every instance, under certain conditions of operation the generator either overran the engine or served to retard the operation of the same. One object of the present invention is to overcome these deficiencies in operation and provide a generator whereof the speed-torque curve will substantially coincide with the power curve of the engine. Accordingly the characteristics of the generator are varied by suitable changes in the field, dependent upon the engine output so that it corresponds approximately to the power output of the engine.

Another object of the present invention is the regulation of the engine speed to maintain it between certain predetermined points, for instance, with respect to a particular engine between the most economical speed for that engine say around 1400 R. P. M. and its maximum horsepower speed, say around 2000 R. P. M. With gas electric drives as at present constituted when a greater effort is required as the vehicle begins the ascent of a hill, there is a reduction in the engine speed because of the greater load upon the engine while the consumption of current increases. This is due to the use of a type of winding of the generator field which does not break down the voltage sufficiently rapidly. Thus, if the hill is steep enough or the load on the vehicle great enough the engine will die down below its most economical speed which must then be increased to a speed exceeding the maximum horse power peak to obtain the requisite generator output. Fuel is thus con-

sumed without return and electric heat losses generated without gain.

According to the present invention these disadvantages are eliminated and the object attained by the provision of means dependent upon the output of the generator, to maintain the engine within a predetermined speed range. More particularly, the shunt field in a compound wound generator having a cumulative series field is weakened, say, by the interposition of resistance in the shunt field circuit. This may be effected by a series current relay operable upon a predetermined current value. The relay may also effect the energization of a teaser field circuit for the generator. Both of these operations serve to reduce the generator loading and permit thereby an increase in the engine speed.

The invention also seeks to provide a motor and associated electrical parts which shall afford a high starting torque and also give a higher vehicle speed at lower engine speeds. To this end a second relay serving as a voltage regulator may be associated with the motor which weakens the motor fields at predetermined voltages corresponding to a vehicle speed obtained with the maximum engine speed described above (i. e.) 2000 R. P. M. This relay is operated by the voltage across the generator circuit and upon a predetermined voltage opens the shunted circuit on the compound series field winding to obtain the necessary current in the shunt field by the use of the compound series winding. The relay may also have a contact which closes and places a shunted resistance across the fields of a motor having a high torque ratio winding to afford a greater starting torque and also give higher vehicle speeds at lower engine speeds.

If desired the current relay may be replaced by two or more relays operable upon different current values where the drop in the engine speed from the maximum to its most economical speed in one step is disadvantageous.

In order that the invention may be clearly understood reference will now be had to the accompanying drawings, illustrating preferred embodiments thereof, wherein:

Figure 1 is a diagrammatic view showing a wiring diagram for a generator and motor in a gas-electric drive according to the present invention.

5 Figure 2 is a diagrammatic view similar to Figure 1 but showing a modification of the wiring and the incorporation of a second current relay.

10 Figure 3 is a view showing a graph indicating engine performance at predetermined time intervals in a gas-electric drive according to the present invention.

15 Figure 4 is a view showing a graph illustrating the effect of the operation of one of the current relays upon the voltage, current and power curve of a particular gas-electric drive when the vehicle is traveling along on level ground.

20 Figure 5 is a view similar to Figure 4 but showing the results obtained in climbing a hill.

25 Assuming now that the vehicle is stationary with the engine not in operation the engine is first started in the usual manner while the field circuits of the generator are open. A controller, not shown, is then closed and thereby the series field is slightly energized while the shunt field has practically no energization. At this point the engine is idling, 30 say, at about 250 R. P. M. In this condition to move the vehicle while the engine is throttled down, it is necessary, as is well understood, to energize the teaser field.

35 The tickler field winding *a* on the generator is availed of to give a quicker building up of the voltage as soon as the accelerator pedal is pressed. The tickler field current is supplied by the battery *b*. With present drives the battery is connected all the time the engine is in operation. To save this battery current and still be able to use a larger amperage to give a quicker pick up, an automatic switch *c* is used to close the circuit on the first predetermined movement of the accelerator pedal *c'* and break the circuit again 40 so soon as the generator voltage has built up. The particular form taken by the switch forms no part of the present invention. As 45 illustrated it forms the subject matter of a co-pending application by the present applicant, U. S. Ser. No. 112,515 filed May 29, 1926, now Patent No. 1,646,764, dated October 25, 1927. This switch not only saves the battery current but since the circuit is normally broken no energization of the generator 50 which would set the vehicle in motion is possible when the engine is idle as would be the case where a separate exciter was associated with the generator. Doing away with a separate exciter also reduces the weight of the vehicle since an exciter weighs two hundred pounds or more, its initial cost is considerable and its maintenance cost, because of the exciter brushes and commutator is no small additional item. Furthermore by the present

construction there is a gain in performance since the engine is enabled to deliver more horsepower in a given time.

Assuming now that the engine is in operation and the vehicle proceeding, the excitation of the tickler field winding having ceased, the power curve of the engine is indicated in full lines between *o* and the roman numeral I in Figure 3. The excitation of the tickler field having ceased say when the engine has attained its most economical speed of about 1400 R. P. M. With an increase in the work to be done as when the vehicle load is increased or a hill is to be ascended, the relay *d* is adapted to function. This relay is a series current relay and operates at a predetermined current value, say 165 amperes to reduce the generator loading and allow the engine to speed up and operate at a more efficient point on its power curve, say 1950 R. P. M. When the current has reached the relay closing point the relay which is operated as will be understood by the main generator current, closes the contacts *d'* to cut in the excitation of the tickler field and opens the contacts *d''* which results in the interposition of a resistance *e* through the shunt field circuit *f*.

When the vehicle has arrived at the top of the hill or has accelerated so that less power is required for its propulsion relay *d* drops back again closing contacts *d''*, say when the current is reduced once more to below 165 amperes, to short circuit the resistance *e*. In the power curve Figure 3, the maximum horsepower speed is indicated by the full lines at the point marked by the roman numeral II. As shown by the curve at point III the generator loading results in an increase in the engine loading which reduces the engine speed to the most economical one say between 1200 to 1400 R. P. M.

This relay *d* also has a contact *d''* which closes the tickler field circuit to give a stable shunt field for very heavy loads, such as climbing a steep grade when the generator is called upon to deliver a large amperage at a low voltage.

Relay *g* is incorporated for the purpose of saving from 500 to 1000 watts in the shunt field exciting current by using the compound series winding for the necessary excitation. There is also obtained a higher voltage at a lower engine speed. This relay is a voltage relay and is designed to function at a voltage of 230 to open the shunted circuit *h* on the compound series field winding of the generator and to open the contacts *g'* to interpose a resistance *i* in the shunt field *f*. This will also materially reduce the rise in temperature of the generator since the temperature in the shunt field is the highest due to the fact that the shunt field windings are of as low a resistance as possible to give a quick pick up. Although generally rated at 125 volts, it is

found that the voltage measures between 250 and 300 volts at high vehicle speeds. Relay g is also adapted to close a contact g^2 to place a shunted resistance j across the motor field k which has a special high torque ratio winding to give a greater starting torque. This will also give higher vehicle speeds at lower engine speeds. The effect of the voltage relay upon the engine power curve is illustrated in Figure 3 between the roman numerals IV and V. As the momentum of the vehicle increases and the work to be performed by the engine and generator proportionately decreased the engine speed increases as shown by the power curve between the points III and IV until the maximum horsepower speed of say 1950 R. P. M. is attained whereupon the relay g interposes the resistance i in the generator shunt field f and opens the shunted circuit h on the compound series field winding. In addition relay h closes the contacts g^2 which place a shunted resistance j across the motor field. The motor field is weakened at a predetermined voltage say of 230 corresponding to a vehicle speed obtained with the efficient maximum horsepower engine speed of say 1950 R. P. M. If this were not done the engine speed would exceed the maximum horsepower peak beyond which energy is wasted. It will be seen that the loading of the generator and the motor causes a decrease in the engine speed from the points IV to V at which latter point the characteristic of the power curve approaches the economical engine speed. Upon a reduction in the voltage say to 200 volts relay g is no longer energized, the contacts g^1 and g^3 are closed and the contacts g^2 opened which short circuits the resistance i and opens the shunted circuit j .

The power curve for the particular internal combustion engine under consideration is indicated in full lines in Figure 3. It will be observed that, through the instrumentality of the relays, the actual power curve for the engine is maintained between the predetermined maximum and minimum engine R. P. M. By the interposition of additional series current relays the characteristics of the actual power curve may be smoothed out considerably. This is accomplished by doing in two steps what was heretofore done in one. In Figure 3 a power curve is shown in dotted lines illustrating the characteristics of the engine with two series current relays l and m interposed in the electrical circuits instead of the one described. Such a wiring diagram is shown in Figure 2.

Relay l is also operated by the main generator current, being provided with a series coil. It opens the contacts l^2 at a predetermined current, say 150 amperes, thereby interposing the resistance n through the shunt field circuit and thus reducing the generator loading and allowing the engine to speed up

and operate at a more efficient point in its power curve, somewhat around 1700 R. P. M. This increase in engine speed is indicated in the graph in Figure 3 by the power curve shown in dotted lines between the point 1, 70 where the relay l operates, and the point 2. When the current is reduced, less power being required for any reason, the relay closes, short circuiting the resistance n and again creating a full shunt field for the generator and thereby loading up the engine and reducing its speed as shown by the curve 2-3 to approximately that of the ideal power curve. During this period, of course, the contacts m^2 are closed to complete the shunt field circuit. Should more power be required, as when a heavy grade is to be ascended, the second relay m is adapted to operate. This relay also has a series coil and is operated by the main generator current when that current value reaches say 200 amperes. At such a current value the contacts m^2 are opened thereby interposing the resistance n' in the shunt field circuit to weaken the shunt field and in addition closes the contact m' of the teaser field circuit a . Through the instrumentality of a weakened shunt field and the energization of the teaser field winding a , a stable shunt field is availed of for very heavy loads. Thus the characteristic of the engine power curve which at the instant the relay m operates may be indicated by the point 3 are enabled to change as shown by the dotted line 3-4, the engine speeding up to its maximum efficient speed say around 1700 R. P. M. as shown by the ordinate of the point 4 in the graph, Figure 3. When the current is reduced below 200 amperes as when the work required of the drive is less the relay m again opens, closing the contacts m^2 to short circuit the resistance n' and permit the generator to again operate with a shunt field of full strength. The operation of the motor relay, and the voltage relay, is as described hereinbefore.

Figures 4 and 5 illustrate the current, engine power and voltage curves from the vehicle at rest to a point just beyond the operation of the current relay, Figure 5 being with respect to the operation of the transmission when the vehicle is on a level and Figure 4 when the vehicle is ascending a grade. The figures have been inserted for reference in an understanding of the operation just described.

It will thus be seen that a transmission for gas-electric driven vehicles has been provided in which the engine and generator are automatically co-ordinated in order that the engine may at all times operate at its most efficient point.

Various modifications may be made in the characteristics and number of the elements going to make up the controlling devices as a whole dependent upon the units with which

they are associated and no limitation is intended by the foregoing description or accompanying illustrations except as indicated in the appended claims.

5. What is claimed is:

1. In a drive for motor vehicles, in combination, an engine, a generator driven thereby, a motor and means operable upon a predetermined excess voltage to weaken the motor field and upon a predetermined minimum voltage to strengthen the field, whereby the engine speed is maintained within a predetermined range dependent upon the voltage off of the motor.
15. 2. In a drive for motor vehicles, in combination, an engine, a compound wound generator having an accumulative series field, an auxiliary exciting means, a motor, means to weaken the shunt field circuit of the generator dependent upon the value of the current delivered to the motor, and means simultaneously to cause the generator to be excited by the auxiliary means.
25. 3. In a drive for motor vehicles, in combination, an engine, a compound wound generator having a shunt field, an accumulative series field, and a teaser field winding, a motor, a resistance, a source of electrical energy for the teaser field, and a current relay having a coil in series with the main generator circuit and operable to interpose the resistance in the shunt field circuit and energize the teaser field upon a predetermined current value.
35. 4. In a drive for motor vehicles, in combination, an engine, a compound wound generator having a shunt field and an accumulative series field, a motor, means to vary the excitation of the series field at a predetermined voltage of the generator, and means to weaken the shunt field upon a predetermined voltage output of the generator.
45. 5. In a drive for motor vehicles, in combination, an engine, a compound wound generator having a shunt field and an accumulative series field, a motor, means to vary the excitation of the series field at a predetermined voltage of the generator, a resistance and a relay operable upon a predetermined voltage output of the generator to interpose the resistance in the shunt field circuit.
55. 6. In a drive for motor vehicles, in combination, an engine, a compound wound generator having an accumulative series field, a motor, a resistance circuit shunted across the series field, a relay operable upon a predetermined voltage, and contacts carried thereby to open the shunted resistance circuit upon operation of the relay.
65. 7. In a drive for motor vehicles, in combination, an engine, a generator, a motor having a series field winding, a resistance circuit and a relay operable upon a predetermined voltage to connect the resistance circuit across the motor field.
75. 8. In a drive for motor vehicles, in combi-

nation, an engine, a compound wound generator having a shunt field, an accumulative series field, and a teaser field winding, a source of electrical energy, an accelerator pedal for the engine and means to connect the source of electrical energy with the teaser field throughout a predetermined movement of the accelerator pedal.

70. 9. In a drive for motor vehicles, in combination, an engine, a compound wound generator having a shunt field, an accumulative series field, and a teaser field winding, a motor having a high torque ratio winding, a resistance circuit for the motor field, a source of electrical energy, a resistance circuit, a series relay operable upon a predetermined current value in the generator circuit, contacts operated by the relay to interpose the second resistance circuit in the generator shunt field and to connect the source of energy with the teaser field, a third resistance circuit, and a second relay operable upon a predetermined voltage off of the generator, contacts operated by the relay to interpose the third resistance circuit in the generator shunt field, and place the first resistance circuit across the motor field.

75. 10. In a drive for motor vehicles in combination, an engine, a generator, driven thereby, series and shunt fields for the generator, a motor, a field for the motor and means operable upon a predetermined excess voltage to weaken the motor field and generator shunt field and strengthen the generator series field, and upon a predetermined minimum voltage to strengthen the first two and weaken the last, whereby the engine speed is maintained within a predetermined range dependent upon the voltage of the motor.

80. 11. In a drive for motor vehicles, in combination, an engine, a compound wound generator having a shunt field, an accumulative series field, and a teaser field winding, a source of electrical energy, an accelerator pedal for the engine, means to connect the source of energy with the teaser field throughout a predetermined movement of the accelerator pedal, and auxiliary means to connect the source to the teaser field upon a predetermined generator current.
